COMBINATION LIQUID DISPENSER, SPRING CLIP
ATTACHMENT AND CLEANING BRUSH

Edward J. Grant, Racine County, Wis., assignor to
S. C. Johnson & Son, Inc., Racine, Wis.

Filed Jan. 6, 1966, Ser. No. 498

Term of patent 14 years

(Cl. D9—2)

FIG. 1 is a top plan view of a combination liquid dispenser, spring clip attachment and cleaning brush embodying my new design;

FIG. 2 is a side elevational view thereof; and

FIG. 3 is a perspective view thereof.

The side not shown has substantially the same appearance as the side shown.

I claim:

The ornamental design for a combination liquid dispenser, spring clip attachment and cleaning brush, substantially as shown and described.
